UNITED STATES PATENT OFFICE

2,435,917

FIBRE REINFORCED COLLAPSIBLE
CONTAINER

Philip Zalkind, New York, N. Y.

Original application February 26, 1943, Serial No.
477,203. Divided and this application March
24, 1944, Serial No. 527,878

3 Claims. (Cl. 229—34)

1

This invention is a division of my application Serial No. 477,203, filed February 26, 1943, and relates to collapsible containers of the casing and drawer type adapted to co-act to form file cabinet sections which may be stacked one upon the other and more particularly to structures comprising non-metallic materials.

A drawer of the class described is shown in my Patent No. 1,946,516 issued February 13, 1944, such drawer being fashioned from a cut and scored corrugated board blank, as fully described therein.

The object of my invention is the provision of structural elements for collapsible drawers wherein facing may be applied to the drawer front in a secure and novel manner.

Figure 1 is a bottom view of the blank for forming the drawer, substantially as shown and described in my Patent No. 1,946,516.

Figure 2 is a cross-sectional view taken on line 2—2 of Figure 1 looking in the direction of the arrows.

Figure 3 is a front view of the front panel of the drawer before the reinforcing facing sheet is secured thereto, the outline of the facing sheet being shown in dotted lines.

The front panel of the drawer may be finished off in any suitable manner in order to improve the appearance thereof. While in prior collapsible drawer construction, such as that shown in my Patent No. 2,152,676, a metal facing sheet was utilized, owing however to the scarcity of metal for the ordinary file cabinet construction uses at the present time, I have devised a method for facing the drawer front by means of a fiber sheet, preferably a pressed paper board such as hard board or the like. The front panel 149 of the drawer of Figure 1 has secured to the outer face thereof a hard board facing sheet 150. This sheet, as will be noted particularly in the cross-sectional view of Figure 2 extends beyond the boundaries of the front panel, so that when the drawer is folded up into erected condition, the extending hard board sheet provides a rabbeted formation which may bear against the front end of a container, as shown in my Patent No. 2,152,676.

In the construction here shown the inner front panel 151 of the drawer carries a handle 152 secured thereto. When the inner front panel is folded up around the hingeline 155, the handle 152 registers with the opening 156 in the outer front panel and facing sheet so that the handle is, while recessed in the opening 156, nevertheless accessible therethrough, as shown in Patent No. 1,946,516.

The facing sheet 150 may be secured to the front panel in any suitable manner, preferably by adhesive. However, as the drawer is pushed into the casing, the abutment of the outer edges

2

of the panel 150 against the outer edge of container or a rabbet within the front thereof (not shown) would tend to tear the outer facing sheet from the drawer front.

Accordingly as shown in Figure 3, I may so arrange the drawer front 149 that the facing sheet 150 cannot thus be removed therefrom. For this purpose I cut out a plurality of tabs 160, 160 from slots in the two vertical sides and in the bottom surface of the front wall 149, tabs being foldable at the fold lines joining panel 149 with the side wings and the drawer bottom.

The tabs 160 are bent outwardly into approximately the plane of the front panel 149 so that the tabs 160 thus form extensions as shown in Fig. 3. The facing sheet 150 is then secured over the front surface 149 and to the tabs 160 which project beyond the boundaries of the front surface. When the drawer is now forced in so that the front thereof bears against the reinforcements, the striking force against the reinforcement is taken up against the tabs 160 which are secured respectively to the side wings and the bottom wall and which in turn carry the facing sheet 150.

Since these tabs 160 are thus substantially integral with the drawer sides and bottom, the force necessary to tear them off would be much greater than the force needed merely to remove the adhesively secured panel 150 of the drawer front. In addition, no force need be taken up by this adhesive securing of the facing sheet 150 since the tabs 160 take up this impact.

Accordingly, by this means accidental removal of the facing sheet 150 is prevented.

In the foregoing I have set forth my invention in connection only with preferred embodiments thereof. Many variations in the formation of the various elements and in the adaptation thereof to various collapsible structures should now be clear to those skilled in the art. I therefore prefer to be bound not by the specific descriptions herein set forth, but only by the appended claims.

45 I claim:

1. A drawer front comprising a panel having an exterior face; a bottom wall connected to said panel; and side wall members connected thereto; at least one tongue cut out of said panel adjacent said bottom wall and each of said side wall members; said tongues being connected to said side wall members and said bottom wall and being folded through 180° into the plane of said panel and extending beyond the edges of said panel; a facing sheet secured to said panel and said tongues, said facing sheet being disposed on said exterior face of said panel whereby to form the front of said drawer and said tongues being secured to said facing sheet on the side thereof contiguous with said exterior face, where-

in said facing sheet is substantially similar in shape to said panel and of sufficient dimension to provide a marginal boundary when said facing sheet is secured to said panel, said tongues being secured to said marginal boundary.

2. A drawer front comprising a panel having an exterior face; a bottom wall connected to said panel; at least one tongue cut out of said panel adjacent said bottom wall, said tongue being connected to said bottom wall at a fold line between said panel and said bottom wall; and said tongue being folded out through 180° into the plane of said panel and extending beyond the boundary of said panel; a facing sheet secured to said panel on the exterior face thereof and said tongue being secured to said facing sheet whereby outward pressure thereon will be resisted by said bottom wall, wherein said facing sheet is substantially similar in shape to said panel and of sufficient dimension to provide a marginal boundary when said facing sheet is secured to said panel, said tongue being secured to said marginal boundary.

3. A drawer front comprising a panel having an exterior face; a bottom wall connected to said panel; and side wall members connected thereto; at least one tongue cut out of said panel adjacent a side wall member; said tongue being con-

nected to said side wall member and being folded through 180° into the plane of said panel and extending beyond the edge of said panel; a facing sheet secured to said panel and said tongue, said facing sheet being disposed on said exterior face of said panel whereby to form the front of said drawer and said tongue being secured to said facing sheet on the side thereof contiguous with said exterior face, wherein said facing sheet is substantially similar in shape to said panel and of sufficient dimension to provide a marginal boundary when said facing sheet is secured to said panel, said tongue being secured to said marginal boundary.
